UNITED STATES PATENT OFFICE.

HENRY PROPACH, OF NEW YORK, N. Y.

DRESS-CHART.

SPECIFICATION forming part of Letters Patent No. 278,180, dated May 22, 1883.

Application filed January 15, 1883. (No model.)

To all whom it may concern:

Be it known that I, HENRY PROPACH, a citizen of the United States, residing in New York, in the State of New York, have invented 5 a new and Improved Dress-Chart, of which the following is a specification.

The nature of my invention consists in the combination of a number of templets joined together by suitable studs working in slots in 10 the adjoining templets, to enable the regulation of the position of said templets toward each other, so as to increase or to diminish the size of the chart according to the dimensions required. The templets and connecting-bars are provided with the usual marks and 15 figures to regulate the same.

In the accompanying drawings, Figure I represents the dress-chart connected together, and Fig. II represents the outlines of the pattern for a dress to be cut according to certain 20 measurements.

Similar letters represent similar parts in all the figures.

The dress-chart consists of a number of templets, A B C D E F G, and rods or bars H, J, K, N, and P, connected together by suitable pins or studs, a b c d, &c., moving in suitable 25 slots, a' b' c' d', &c., in the adjoining parts, whereby said templets can be easily moved 30 farther apart or nearer together, according to certain measurements. The templets and the rods or bars are provided with suitable scales, engraved or printed upon the same, corresponding with the measure used to take the 35 measure of the body, and whereby the exact position of the several templets are fixed, such as the bust-measure, chest-measure, back-width, waist-length, back-length, front, belt, and hip measure. When the several templets 40 have been regulated to correspond with the measure of the body and fixed in relation with each other, the desired pattern can be readily drawn upon the material, or preferably upon a sheet of paper, from which it is marked upon 45 the material by following the outer edges of the chart, and the figure represented in Fig. II will be obtained.

In Fig. I the templets and bars forming the dress-chart are placed in accordance with

the following measure, viz: bust-measure, 50 round the largest part, under the arm, across the chest, tight to keep measure together, 34; chest-measure, taken from one arm to the other over the stoutest part, across the chest, 16 $\frac{1}{2}$; back-width, over the broadest part of 55 back, from armhole to armhole, 11; waist-length, from the armhole to the beginning of the hips, 7; back-length, from the neckband to the middle of the back-waist, 15; shoulder-length, from the beginning of the waist-length 60 in back over the shoulder three inches from the neck to the middle of the front, 30; front, from the back-band to the width of the waist in front, 19; belt-measure, round the smallest part of the waist, 24; hip-measure, five inches 65 under the waist, over the shortest part of the hip, 40. Draw the indicator to 34 on scale M, the bust-measure, when it will be found that the edge of templet A stands on 31 on scale Q. Then put templet D on 16 $\frac{1}{2}$ on scale R 70 for the chest-width. Place templet C on 11 on scale S for back-width. Place lower edge of templet B on 15 on bar N for back-length. Move templet E so that edge of templet C comes to 30 on division 7 for shoulder-length, and in 75 the same position place templets F and D. Put inner edge of templet E on 34 (bust-measure) on bar H, likewise inner edge of templet F on 34 on bar J, and pin m at end of bar J on line 34 on templet G. The position of bar 80 H will cause the moving of pin k at its other end in the slot k' of bar K, as here represented, to 2 $\frac{1}{2}$. Then take 2 $\frac{1}{2}$ from 19—the true front-measure—and place lower edge of templet A on this remaining number, 16 $\frac{1}{2}$, for this 85 measure. The chart will now be in position to draw the outline of the figure represented at Fig. II. Mark upon the paper before removing chart, points 34 on top of templets D and C, and likewise at bottom of templets A 90 and B; likewise points 34 on scales V and W, and on scale Y on templet A. Then mark a point about half-way between 34 on templet C, and 34 on templet E at inner edge, and at 34 on scale X of templet B, when the chart 95 may be removed. Points 34 of scales V and W show the position for placing templet to form breast-folds.

What I claim as my invention, and desire to secure by Letters Patent, is—
The combination of the templets A B C D E F G and rods or bars H J K N P, connected together by suitable pins or studs arranged to move in slots provided in the templets and bars, respectively, said parts being also pro-

vided with suitable scales, and all constructed and arranged for operation substantially as and for the purpose specified.

HENRY PROPACH.
